SELF LOCKING RECEPTACLE AND PLUG FOR ELECTRICAL WIRING DEVICES

Harvey Hubbell and Benjamin C. Webster, Southport, Conn., assignors to Harvey Hubbell, Incorporated, Bridgeport, Conn., a corporation of Connecticut
Filed May 25, 1959, Ser. No. 815,502
4 Claims. (Cl. 339—189)

This invention relates to electrical wiring devices of the type for making detachable electrical connections, and particularly to those having interlocking means which prevent the accidental separation of the connecting parts during use thereof.

Interlocking electrical connectors are known in the art, and usually comprise two connecting parts which carry electrical contacts that engage each other on relative longitudinal movement of the parts toward each other to cause electrical connection, the electrical contacts on one of the parts being designed to interlock with a portion of the other part thereafter on the occurrence of relative rotation of the parts. An excellent example of a highly commercially successful electrical connector of the foregoing type is set forth in Patent No. 1,771,729 of Harvey Hubbell, Jr., granted July 29, 1930, entitled Interlocking Plug and Cap. Whereas this type of electrical connector is entirely satisfactory for its intended purpose, it does require two distinct movements on the part of the user to effect interlocked electrical connection, viz., first, longitudinal pushing of the connector parts toward each other, and, a second turning of the parts relative to each other.

It is an object of this invention to provide an improved interlocking electrical connector wherein interlocked connection of connector parts can be effected by the single motion of pushing the connector parts longitudinally toward each other.

The object of this invention is achieved in one form by incorporating in known interlocking electrical connectors resilient means which automatically acts on one or more of the electrical contacts of one of the connector parts after the parts are moved longitudinally toward each other to make electrical connection, to cause the parts to rotate relative to each other to effect interlocking.

The above and other objects of our invention and further details of that which we believe to be novel and our invention will be clear from the following description and claims taken with the accompanying drawings, wherein:

FIG. 1 is a side elevational view of the two main parts of an interlocking electrical connector which incorporates our invention;

FIG. 2 is a front elevational view on an enlarged scale of one modification of one of the parts;

FIG. 3 is a fragmentary side elevational view of the connector part shown in FIG. 2, with portions broken away and shown in section for the sake of clarity;

FIG. 4 is a bottom plan view of the connector part shown in FIG. 2 after the base plate thereof has been removed;

FIG. 5 is a sectional view taken substantially on line 5—5 of FIG. 3;

FIGS. 6, 7 and 8 are fragmentary sectional views illustrating the operation of the FIG. 2 modification;

FIG. 9 is a side elevational view similar to FIG. 3 of a second modification of one of the connector parts;

FIG. 10 is a sectional view taken substantially on line 10—10 of FIG. 11; and

FIGS. 11, 12 and 13 are fragmentary sectional views illustrating the operation of the FIG. 9 modification.

Referring to the drawings, it will be observed by those skilled in the art that the invention has been illustrated

2

as being incorporated in an electrical connector of the receptacle and plug type, and that two modifications of one of the connector parts are illustrated as comprising two alternative structural versions of the electrical receptacle. It should be understood that, if desired, the invention may be readily incorporated into other electrical connectors, such as electrical connector and cap assemblies and the like.

In FIG. 1 there is generally illustrated an electrical connector which incorporates the instant invention, in the form of an electrical plug 10 and an electrical receptacle 12. The plug 10 comprises a disk-like dielectric body member 14 which supports a plurality of current-carrying electrical terminal and contact units 16 on one side thereof. Each of the units 16 comprises an electrical terminal portion (not shown) which is rigidly secured to the member 14 on one side thereof, and a male electrical contact finger 17 which projects away from the member 14. The contact fingers 17 are spaced circumferentially, and on the same lateral side of each of the contact fingers 17 there is formed a laterally projecting portion 18 which constitutes a part of the connector interlocking means, the detailed construction and operation of which will be set forth subsequently. On the other side of the member 14, a cable clamp 20 is mounted and functions to secure the electrical cable 22 to the member 14. The clamp 20 may be of any known design, and the member 14 is provided with a central opening (not shown) which allows an end of the cable 22 to pass therethrough to the side thereof on which the terminal portions of the units 16 are disposed, where the cable leads (not shown) may be connected to said terminal portions in any suitable known manner. The other end of cable 22 (not shown) may be wired to any suitable electrical component.

The receptacle 12 generally comprises a socketed dielectric body member 24 which includes a raised circular slotted front wall 25 on the front thereof and a detachably mounted dielectric base plate 26 on the rear thereof. The member 24 and base plate 26 may be conveniently detachably secured to each other by the screws 28 which are received in appropriate cooperating openings formed in the member 24 and the base plate 26, and threaded in threaded openings formed in the mounting ear brackets 30 that are disposed on the front of the member 24 on the sides of raised wall 25. Brackets 30 are adapted to receive mounting screws 32 in openings formed therein for the purpose of mounting the entire receptacle 12 on any convenient supporting wall.

As illustrated, the plug 10 and receptacle 12 are designed to make interlocked electrical connection for a wired device having four-wire cable, and therefore, there are four electrical terminal and contact units 16 formed on the plug 10 and four cooperating electrical contact making and interlocking means, which will be described subsequently, formed on the receptacle 12. It will be understood by those skilled in the art that wired devices with cables having numbers of wires other than four, such as two or three wires, may have the instant invention incorporated therein.

Receptacle 12 includes means for making electrical contact with the plug and means for interlocking the plug and receptacle when they are connected. The electrical contact making means on the receptacle 12 comprises four electrical terminal and contact units 34 which are disposed in an appropriate spaced manner in the receptacle body member 24, and each of which comprises a spring clip female contact portion 36 and a terminal portion 38. As can best be seen in FIG. 2, the receptacle front wall 25 has four arcuate slots 40 formed therein which are adapted to receive the plug contact fingers 17 when the connector parts are connected. One of the slots 40 has a radially extending portion 42 which may cooperate with

a radially projecting portion 44 formed on one of the plug contact fingers 17 (see (FIG. 1) to aid in properly aligning the plug and receptacle during their connection. The slots 40 are disposed to communicate with four socket-like cavities 46 formed in the receptacle body member 24 by walls thereof and which house the units 34. The cavities 46 each contain laterally oppositely extending portions 48 and 50 and a radially outwardly extending portion 52; in the context of the illustrated form of the invention, the term "laterally" means "circumferentially." The entire cavities 46 open on the rear side of the body member 24 and are adapted to be closed on that side by base plate 26 when the receptacle 12 is fully assembled. As can best be seen in FIG. 2, the cavity portions 48, when the receptacle is viewed from its front, are covered by portions of front wall 25, whereas cavity portions 50 are not covered by front wall 25, and therefore are directly accessible through slots 40. The slots 40, cavities 46 and units 34 are structurally and dispositionally related so that the open ends of the U-shaped spring clip female contact portions 36 face the slots 40, and therefore, are disposed to make electrical contact with the plug contact fingers 17 when the plug is moved longitudinally toward the receptacle 12 and the fingers 17 are appropriately and sufficiently inserted into the receptacle slots 40. It will be observed that the slots 40 are wide enough (their circumferential dimension) to accommodate the plug contact fingers 17 and their lateral projecting portions 18. When engagement is made between the plug contact fingers 17 and the receptacle female contact portions 36, the legs of the female contact portions 36, which are inherently flexible, flex radially, and the cavity portions 52 provide room for such flexure.

It will, therefore, be apparent that with the electrical connector structure described thus far, in order to effect electrical connection, the plug 10 and receptacle 12 are moved longitudinally toward each other, and that this results in the plug contact fingers 17 being inserted and received between the flexible legs of the female contact portions 36 of the units 34. In order to effect interlocking of the plug and receptacle in known prior art interlocked electrical connector constructions, such as the referred-to patent to Harvey Hubbell, Jr., it is necessary to rotate (turn) one of the connector parts, e.g., the plug, relative to the other connector part, e.g., the receptacle, after the connector parts have been moved longitudinally (pushed together) toward each other as far as they can go and electrical connection of the connector parts has been made. For convenience in understanding the operation of known prior art devices, reference may be had to FIGS. 2 and 5. Relative rotation of the connector parts results in the plug contact fingers 17 and their projecting portions 18 being rotated clockwise relative to the cavities 46 in the receptacle body member 24, but electrical contact between the connector parts is continuously maintained. Such relative rotation results in the projecting portions 18 being moved laterally to positions wherein they are disposed under the portions of the receptacle front wall 25 which overlie the portions 48 of receptacle cavities 46. When the connector parts are in this position, longitudinal movement of the connector parts away from each other (intentional or unintentional pulling apart) will not result in disconnection of the parts, because the projecting portions 18 make interference contact with the inner surfaces 53 of the front wall portions that overlie the cavity portions 48. It will be understood that reference to FIGS. 2 and 5 and the above explanation with relation thereto is for the purpose of convenience in understanding the operation of known prior art devices and not intended to be a description of the operation of the illustrated improved interlocking electrical connectors contemplated by the instant invention.

The structure and operation described thus far is the prior art setting for the instant invention, which is an improvement on such known prior art interlocking electrical

connectors. The instant invention contemplates the addition and incorporation of novel structure into the described known prior art connectors which eliminates the necessity of the user's turning the connector parts relative to each other to effect interlocked connection thereof after the connector parts have been pushed together. This novel structure comprises means for automatically causing relative rotation of the connector parts after the connector parts have been moved sufficiently longitudinally toward each other. In both modifications of the illustrated form of the invention, this novel structure is incorporated into the receptacle and comprises resilient camming means which is associated with some of the receptacle female contact portions 36 and which cooperates with some of the plug contact fingers 17 to cause relative rotation of the connector parts at the proper time during connection thereof. This is the preferred form of both modifications of the invention. However, it will be understood by those skilled in the art that novel structure for causing automatically such rotation could be readily incorporated into the plug, as by being associated with the plug contact fingers 17, without departing from the spirit of the invention.

As illustrated in the preferred form of the modification set forth in FIGS. 2 to 8, the resilient camming means comprises a pair of bow-shaped leaf springs 54 which are illustrated as being associated with two alternate units 34. Fewer or more leaf springs 54 may be employed depending on their strength, the illustrated arrangement including two leaf springs having been found successful in practice. As illustrated, each leaf spring 54 is structurally incorporated into a different unit 34 by having one end 56 bent and rigidly attached to a flat base 58 of a unit 34 and the base of a female contact portion 36, as by the rivet 60, as can best be seen in FIG. 3. The bowed central portion 62 of the leaf spring 54 normally is disposed to extend near adjacent edges of the legs of its associated female contact portion 36. The free ends 64 of the leaf springs 54 respectively contact radial wall portions 66 which in part define the portions 50 of the receptacle cavities 46, and the wall portions 66 function as backing walls for the leaf springs.

The leaf springs 54 function to cause automatic rotation of the plug contact fingers 17, and the plug 10, after said fingers are inserted into the slots 40 and cavities 46 a certain amount. This can be best understood by reference to FIGS. 6, 7 and 8, wherein this operation is set forth. In FIG. 6, the condition of the relevant elements of the means for making electrical contact and automatic physical interlocking of the connector parts is shown at the time when the plug contact fingers 17 are initially being inserted into the receptacle slots 40, but before making contact with the female contact portions. It will be observed in FIG. 6 that a rounded corner 68 is formed on each of the plug contact fingers 17, some of which engage an upper end 64 of a leaf spring 54. The normal unstressed condition of leaf springs 46 may also be observed in FIG. 6. Further longitudinal movement of the plug toward the receptacle results in the plug contact fingers 17 being inserted further into the receptacle slots 40 and the receptacle cavities 46. FIG. 7 illustrates such a representative intermediate position, and it will therein be observed that the upper ends 64 of the leaf springs 46, which are free and inherently capable of flexure, have been distorted by the overpowering action of the rounded corners 68 of the plug contact fingers 17, and that the central bowed portions 62 of the leaf springs 46 have also been distorted thereby. Therefore, the leaf springs 46 have been stressed. In FIG. 7 it will be observed that the finger projecting portions 18 have substantially cleared the inner surfaces 53 of the portions of front wall 25 that overlie the cavity portions 48. Prior to reaching the precise FIG. 7 condition, the finger projecting portions 18 were in contact with the edges 70 of the front wall portion which defines receptacle slots 40 and were thereby

prevented from lateral movement and the consequential relative rotation of the plug and receptacle. Therefore, the distortion of the leaf springs 54 illustrated in FIG. 7 results, and the leaf springs are stressed. It will also be observed in FIG. 7 that electrical contact between the connector parts has been made, principally by the finger projecting portions 18 and the female contact portions 62. On clearing the edges 70, the finger projecting portions 18 are free to move into the portions 48 of the receptacle cavities 46, and, in fact, are so moved automatically by the unstressing action of the leaf springs 54. The final positions and condition of the plug contact fingers 17, their projecting portions 18 and the cooperating portions of the receptacle are shown in FIG. 8, wherein it will be clearly seen that the leaf springs 46 have returned to their normal unstressed condition, electrical contact is now principally made by the plug contact fingers 17 and the female contact portions 36, and that the plug and receptacle are connected and interlocked by virtue of the finger projecting portions 18 making interference contact with the inner surfaces 53 of the portions of front wall 25 which overlie the receptacle cavity portions 48. It will, therefore, be observed that both electrical contact and physical interlocking of the plug and receptacle are effected simply by moving these parts longitudinally toward each other, and that this single motion automatically results in the relative rotation of the parts to effect interlocking. It will be understood that when finally assembled, as illustrated in FIG. 8, the parts may not be accidentally disconnected by longitudinal separating forces, and that in order to effect separation, it is necessary to intentionally rotate the parts relative to each other and then pull them apart longitudinally.

It will also be understood by those skilled in the art that while the materials for some of the plug and receptacle elements have been set forth above, all of the elements will be made of appropriate materials, i.e., electrical conducting or insulating materials, and be electrically connected in conventional manners to the electrical leads of the electrical devices, cables and the like, which are wired to them.

FIGS. 9 through 13 illustrate a second modification of the invention, which basically operates on the same principle and in the same manner as the first modification disclosed. Throughout FIGS. 9 through 13, the same reference numerals with a prime (') added will be used to designate corresponding elements of the two modifications which are substantially the same. New reference numerals will be applied to those elements which differ in structure significantly from their corresponding elements in the other modification.

The principal differences in the modification illustrated in FIGS. 9 through 13 from that of the first modification resides in structural alterations made in the receptacle 12', and these differences reside principally in providing alternative structural means for automatically causing rotation of the plug relative to the receptacle when the connector parts are pushed together, as can best be gleaned by comparing FIGS. 9 and 10 to FIGS. 3 and 5, respectively. It should be noted, for example, that the portions 50' in the second modification of the receptacle cavities 46' have been extended laterally to include additional cavity portions 72. The camming shoes 74 are flat members which are pivotally mounted on fixed pivot pins 76 that are supported in the receptacle body member 24' and have portions generally vertically disposed in receptacle cavities 46' and in the additional cavity portions 72, as can be clearly seen in FIG. 9. It will also be there observed that the shoes 74 include lower ends 78 that are pivotally secured to pivot pins 76, which are generally horizontally oriented, upper arcuate cam portions 80, each of which has a vertically extending stop ear 82 at its upper end, and horizontally extending pins 84 formed midway and on one side thereof which function to position one end of coiled compression springs 75

86, the other ends of which make frictional contact with wall portions 88 that partially form the additional cavity portions 72. In order to assist in mounting the compression springs 86, retaining slugs 90 are secured in the additional cavity portions 72 below said springs.

The camming shoes 74 are mounted for oscillation between a normal projecting position, shown in FIGS. 9, 11 and 13, and a retracted position, shown in FIG. 12. The shoes 74 are urged to their projecting position by the compression springs 86, and their projecting limit is fixed by the stop lugs 92 which depend from the front wall 25'. The retracted limit of the shoes 74 is fixed by contact of the stop ears 82 with the wall portions 94 which in part define the additional cavity portions 72.

As pointed out above, the shoes 74 are normally disposed in their projecting position. It will be observed in FIGS. 9 and 11 that in such projecting position, an edge portion of each of the cam portions 80 of the shoes contacts the edges of female contact portions 36', and that the shoe stop ears 82 contact stop lugs 92. If it is desired to connect the plug and receptacle, the plug contact fingers 17' are inserted into the arcuate slots 40', as illustrated in FIG. 11. On further insertion, the rounded corners 68' of the plug contact fingers 17' contact the cam portions 80 of the shoes 74. The effect of such contact is to overcome and distort the compression springs 86 and force the shoes 74 to pivot and retract, thereby stressing the springs 86, as will be seen in FIG. 12. When the projecting portions 18' of the plug fingers 17' clear the edges 70', they are free to be moved laterally automatically by the shoes 74, and, in fact, are so moved, as a result of the compression springs 86 unstressing themselves. FIG. 13 illustrates the connector parts after they have been automatically rotated relative to each other by the shoes 74. When the connector parts are finally connected, the projecting portions 18' of the plug contact fingers 17' make interlocking contact with the inner surfaces 53' of the portions of the receptacle front wall 25' which overlie cavity portions 48'.

The operation of the second modification, illustrated in FIGS. 9 to 13, is substantially the same as that of the first modification, and it generally possesses similar advantages. In both cases, electrical connection and physical interlocking of the connector parts are achieved simply by the single motion of moving the connector parts longitudinally toward each other. Herein lies the principal advantage of the instant invention over known prior art interlocking electrical connectors, which require two distinct motions to effect interlocked electrical connection, viz., (1) pushing the connector parts together, and (2) then turning the connector parts relative to each other.

In view of the foregoing it is believed that the construction and operation of both illustrated modifications of the invention are clear.

As will be evident from the foregoing description, certain aspects of our invention are not limited to the particular details of construction of the examples illustrated, and we contemplate that various and other modifications and applications will occur to those skilled in the art. It is, therefore, our intention that the appended claims shall cover such modifications and applications as do not depart from the true spirit and scope of our invention.

What we claim as new and desire to secure by Letters 65 Patent of the United States is:

1. An interlocking electrical connector comprising: a body of electrical insulation material; a plurality of chambers formed in said body; said body having a front wall with a plurality of spaced openings individually leading to said chambers; a plurality of electrical conducting contacts carried by said body including U-shaped spring clips which are disposed individually in said chambers so as to have their open ends face said openings whereby electrical contact fingers of a second connecting member may be inserted through said openings and into said chambers

to enter and be engaged by the legs of said U-shaped spring clips on longitudinal movement of the second connector member toward said connector member; said openings being wider than the width of normal electrical contact fingers whereby electrical contact fingers having lateral interlocking projecting portions that are adapted to be rotated into interlocking position relative to said front wall after they are fully inserted into said chambers may be inserted therethrough; and retractile resilient means other than said U-shaped spring clips disposed in at least one of said chambers and having a portion near adjacent edges of the legs of one U-shaped spring clip in the path of the electrical contact finger that is arranged to enter the chamber in which said one U-shaped spring clip is mounted to engage an edge portion of the electrical contact finger and laterally bias it between the legs of said one U-shaped spring clip when it is fully inserted into said body, whereby its lateral projecting portion is automatically moved into interlocking position relative to said front wall, and a biasing portion for said portion in contact with a wall of said body which forms the chamber in which said one U-shaped spring clip is mounted which functions to back up the biasing portion; said resilient means comprising a leaf spring that includes a bowed central portion that is disposed near adjacent edges of the legs of said one U-shaped spring clip, an end rigidly secured to said one U-shaped spring clip and a free end that contacts the wall of said body which forms the chamber in which said leaf spring is mounted and functions as a backing wall for the leaf spring.

2. The device defined in claim 1 wherein said one U-shaped spring clip and said leaf spring are part of a unitary contact unit that is bodily removably mounted in a chamber in said body.

3. An interlocking electrical connector comprising: a body of electrical insulation material; a plurality of chambers formed in said body; said body having a front wall with a plurality of spaced openings individually leading to said chambers; a plurality of electrical conducting contacts carried by said body including U-shaped spring clips which are disposed individually in said chambers so as to have their open ends face said openings whereby electrical contact fingers of a second connecting member may be inserted through said openings and into said chambers to enter and be engaged by the legs of said U-shaped spring clips on longitudinal movement of the second connector member toward said connector member; said openings being wider than the width of normal electrical contact fingers whereby electrical contact fingers having lateral interlocking projecting portions that are

adapted to be rotated into interlocking position relative to said front wall after they are fully inserted into said chambers may be inserted therethrough; and retractile resilient means other than said U-shaped spring clips disposed in at least one of said chambers and having a portion near adjacent edges of the legs of one U-shaped spring clip in the path of the electrical contact finger that is arranged to enter the chamber in which said one U-shaped spring clip is mounted to engage an edge portion of the electrical contact finger and laterally bias it between the legs of said one U-shaped spring clip when it is fully inserted into said body, whereby its lateral projecting portion is automatically moved into interlocking position relative to said front wall, and a biasing portion for said portion in contact with a wall of said body which forms the chamber in which said one U-shaped spring clip is mounted which functions to back up the biasing portion; said resilient means comprising a flat shoe that is pivotally secured to said body and includes a cam portion that is arranged near adjacent edges of the legs of said one U-shaped spring clip, and a separate spring means for biasing said shoe.

4. The device defined in claim 3 wherein said spring means comprises a spring that at one end is in contact with said shoe and at its other end is in contact with the chamber forming wall, said shoe is normally biased by said spring into a projecting position wherein it is disposed to be contacted by the electrical contact finger on the occurrence of an initial amount of longitudinal movement of the electrical contact finger into said body and is retractile laterally against the bias of said spring on further insertion of the electrical contact finger into said body until the projecting portions of the electrical contact fingers clear said front wall at which time said shoe is automatically moved to its projecting position and causes the electrical contact fingers to be moved into alignment with said front wall into interlocking position.
